Primary Examiner—Doris Clark

(21) Appl. No.: **29/238,751**

(74) Attorney, Agent, or Firm—G. Andrew Barger

(22) Filed: **Sep. 20, 2005**

CLAIM

(51) **LOC (8) Cl. 25-01**

The ornamental design for a flange-plated hybrid electrical pole, as shown and described.

(52) **U.S. Cl. D25/126**

DESCRIPTION

(58) **Field of Classification Search** D25/126;

FIG. 1 is a perspective view of a flange-plated hybrid electrical pole showing our new design;

174/45 R; D13/139.4, 139.5; 52/726.4

FIG. 2 is a side elevational view thereof;

See application file for complete search history.

FIG. 3 is the opposite side elevational view thereof;

(56) **References Cited**

FIG. 4 is a top plan view thereof;

U.S. PATENT DOCUMENTS

FIG. 5 is a bottom plan view thereof;

411,204 A 9/1889 Short

FIG. 6 is a perspective view of a second embodiment of a flange-plated hybrid electrical pole showing our new design;

595,600 A 12/1897 Buck

FIG. 7 is a side elevational view thereof;

689,387 A 12/1901 Crossland

FIG. 8 is the opposite side elevational view thereof;

732,223 A 6/1903 Rhoades

FIG. 9 is a bottom plan view thereof;

839,272 A 12/1906 Crow

FIG. 10 is a perspective view of a third embodiment of a flange-plated hybrid electrical pole showing our new design;

976,879 A 11/1910 Hughs

FIG. 11 is a side elevational view thereof;

1,244,652 A 10/1917 Southgate

FIG. 12 is the opposite side elevational view thereof;

1,329,026 A 1/1920 Snyder

FIG. 13 is a bottom plan view thereof;

1,542,575 A 6/1925 Perry

FIG. 14 is a perspective view of a fourth embodiment of a flange-plated hybrid electrical pole showing our new design;

1,567,301 A 12/1925 Ross

FIG. 15 is a side elevational view thereof;

1,679,297 A 7/1928 Ehrler

FIG. 16 is the opposite side elevational view thereof; and,

1,870,770 A 8/1932 De Witt

FIG. 17 is a bottom plan view thereof.

1,877,583 A 9/1932 Pfaff

The broken lines are for illustrative purposes only and form

2,036,771 A 4/1936 Pfistershammer

no part of the claimed design.
